R. T. LOWE

TRAIN PIPE COUPLER

Filed May 23, 1925

UNITED STATES PATENT OFFICE.

RICHARD T. LOWE, OF CEDAR BLUFF, VIRGINIA, ASSIGNOR OF ONE-HALF TO BALLARD
I. PAYNE, OF CEDAR BLUFF, VIRGINIA.

TRAIN-PIPE COUPLER.

Application filed May 23, 1925. Serial No. 32,520.

My invention relates to automatic train-pipe couplers. A great obstacle to the practical success of an automatic train-pipe coupler is the non-maintenance of a tight joint at the coupling under the severe operative conditions to which the coupler is subjected, and one of the objects of my invention is to provide a construction which will assure the necessary tightness of the joint to prevent the escape of air or other fluid transmitted through the train-pipes. Other objects of my invention will be understood from the description hereinafter given, and the advantages of my invention will be understood by those skilled in the art.

My invention consists in whatever is described by or included within the terms or scope of the appended claims.

I illustrate and shall describe my invention with especial reference to the automatic coupling of the air-brake pipes, but unless it is excluded by the terms of meaning of my claims, I include as within the scope of my invention couplings for pipes carrying other fluids.

In the drawings:

Fig. 1 is a perspective view of one of the coupling units;

Fig. 2 is a top plan view showing two of the units coupled together;

Fig. 3 is a transverse section on the line 3-3 of Fig. 2.

Describing in detail what is shown in the drawings, it will be seen that my train-pipe coupling is of the duplicate or interlocking type, that is to say, the construction of each unit at each end of the car is the same and each comprising a longitudinally extending member, that is suspended beneath the car-coupler, and each member comprising a flat-sided head portion, 10, and a shank or tail portion, 11, which at its rear end extends through a hole in a plate or bracket, 12, bolted to the underside of the shank of the car-coupler, and between such bracket, 12, and the head, there is a coil spring, 13, on the tail which acts expansively to press the head forward, the tail sliding through the hole in the bracket, 12, and the forward movement of the member being limited by a shoulder, which may be a nut, 14, secured to

the tail in the rear of the bracket, 12, and which engaging the rear side of the bracket, 12, stops the forward movement of the member under the forward pressure of the spring.

The head, 10, at its forward end is bifurcated and formed into upper and lower forwardly and upwardly diverging projections, 15, and on the inner side of the head at the rear is a forwardly projecting finger, 16, that is pointed or tapering and spaced away from the side of the head, so that it will enter between the projections, 15, of the matching or mating head when the two come together and closely embrace the sides of the head in rear of the projections, 15, so that when the two heads come together, they are interlocked against sidewise and vertical movement. The pointed or tapering form of the projections, 16, of course, is to facilitate their engagement, even though at the time the heads come together they are not in alignment, with the part to be engaged.

Upon the outer side of the head a block, 17, is pivoted on a vertical pivot between ears, 18, projecting from the top and bottom of the block, 17, the block extending forward from such ears. The block, 17, has substantially at midlength a horizontal opening or hole in which is mounted the pipe-coupling, 19, such coupling including a head which projects from the block into a hole, 20, in the head, 10, so that its outer face may be brought into contact with the face of the matching coupling, by the inward movement of the blocks, 17, when the two heads are coupled together as herein-after described. The coupling, 19, has a pivotal connection with the block, 17, to allow for adjustment of the face of one coupling to the other taking into account the fact that the block, 17, which carries each, is mounted for pivoting or swinging movement. The pivotal connection consists of round pins, 21, projecting above and below the coupling and each of which is engaged by a bearing-cap, 22, secured by bolts in a recess in the inner face of the block, 17, to enable the easy assemblage and separation of the parts when necessary. The coupling has a rearwardly extending pipe section, 23,

to the end of which is secured the end of the piece of hose, 24, which as usual extends from the train-pipe, 25, forward of the angle-cock, 26. The handle or lever of the 5 angle-cock is connected by an arm, 27, bolted to the head, 10, to partake of the longitudinal movement thereof, so that upon the rearward movement of the head, 10, in a coupling operation, the angle-cock will be 10 opened, and upon a forward movement when uncoupling is done, the angle-cock will be closed. The connection between the arm, 27, and the angle-cock handle is a yieldable one consisting of two coil springs, 15 28, on the opposite sides of the angle-cock to allow greater movement of the head than is necessary to move the angle-cock between its opened and closed positions.

After the coupling heads come together 20 and interlock, as I have described, I press together with great force the couplings, 18, by subjecting the blocks, 17, to powerful pressure by a lever device, that includes for each block a lever, 30, that swings horizontally upon a pivot, 31, mounted between lugs, 32, that project horizontally outward from the head, 10, at the top and bottom thereof, and which at its inner end presses against the side of the block, and at its outer 25 end has pivoted to it a longitudinally extending rod, 33, that passes through a guide hole in the bracket, 12. Upon the rod, 33, is an expansive coil spring, 34, which at one end bears against the forward side of the bracket, 35 12, and at its other end engages a shoulder, 35, on the rod. In the rear of the bracket, 12, the rod has a collar, which is preferably a nut, 36. During the operation of coupling two heads, 10, the springs are compressed 40 allowing the rods to move through them, and carry the nuts, 36, thereon, rearward from the bracket, 12, and thus swinging the lever, 30, in each case against its block, 17, and crowding the gasket faces of the two 45 couplings into air-tight contact, and holding them there. And so long as the car-couplers couple the two cars together, that tight joint is maintained. When the car-couplers are uncoupled, and the cars separate, the train- 50 pipe coupler heads, 10, are not pulled apart until after the bracket, 12, moving rearward engages the nuts, 36, and the rods, 33, are moved rearward, and the levers, 30, are moved away from the coupling carrying 55 blocks, 17. The latter are now free to swing away from one another, to remove the gaskets from contact so that when the heads, 10, then slide past one another, no friction 60 will fall on such gaskets. The blocks, 17, are thus swung outward by coil springs, 37, for the respective heads, 10. Each spring, 37, is mounted upon a pin, 38, attached to the block, 17, and has sufficient length to pass 65 through a horizontal hole, 39, therein, and to enter an aligning hole, 40, in the opposite

head, 10, when the block is moved into joint-forming position by the action of its lever.

The engagement of the tail, 11, with the bracket, 12, supports the coupling member at the rear end, and further forward it is supported from the car-coupler by a coil spring, 41, attached at its end under the car-coupler, and at its lower end engaging an eye, 42, that forms the head of the pivot for the swinging block, 17. 75

Preferably the projection, 16, on each head has such length that when the heads are in interlocking position the projection, 16, will extend in rear of the front end of the block, 17, and to enable the lever, 30, to be passed by such projection, it is bifurcated at its block-engaging end. 80

The gasket is held in place in the coupling by a removable cap, 138, which has a hexagonal or polygonal head, and the hole in the head, 10, in which the coupling is placed has a correspondingly shaped contour to hold said cap from turning. 85

It will, of course, be understood that I do not confine myself to any particular dimensions or proportions of parts, nor to details of construction as there may be departures in these respects without departing from the scope of my claims or some of them. 90

What I claim is:

1. A train-pipe coupler comprising cooperating heads each consisting of a member extending longitudinally of the car, a pipe-coupling for each head, a coupling-carrying-block movably mounted on the head and being substantially parallel with said member, a lever to act upon the block to press the pipe-couplings together, and means to rock said lever in opposite directions automatically. 100

2. A train-pipe coupler comprising cooperating heads each consisting of a member extending longitudinally of the car, a pipe-coupling for each head, a coupling-carrying-block movably mounted on the head and being substantially parallel with said member, a lever to act upon the block to press the pipe-couplings together, means to rock said lever in opposite directions automatically, comprising a longitudinally extending rod connected with the lever, a part moving with the car, a spring exerting pressure on said rod and bearing on said part, and a shoulder on the rod on the opposite side of said part adapted to be engaged thereby. 110

3. A train-pipe coupler comprising a head, a coupling movable back and forth in a hole in said head, a block pivoted to said head and to which said coupling is pivoted, and an automatically rocked lever acting on said block. 120

4. A train-pipe coupler comprising two similar longitudinally extending coupling-carrying heads each consisting of a member 130

extending longitudinally of the car, each having at its forward end upper and lower projections extending in straight lines directly forward, and each having on its side

5 a single projection adapted to enter between the projections at the end of the other head, means to press the couplings together com-

prising blocks pivoted on the opposite sides of the respective heads and extending alongside the same, and automatic means to move 10 said blocks towards each other.

In testimony whereof I hereunto affix my signature.

RICHARD T. LOWE.
